[57] **CLAIM**

The ornamental design for a hand implement, as shown.

DESCRIPTION

FIG. 1 is a side elevational view of a hand implement
made in accordance with our present invention;

FIG. 2 is a view similar to FIG. 1 taken at approxi-
mately right angles to the latter;

FIG. 3 is a view similar to FIG. 2 showing the opposite
side of the hand implement;

FIG. 4 is an end elevational view thereof; and

FIG. 5 is a view showing the opposite end thereof.

Fig. 1.

Fig. 2.

Fig. 3.

Fig. 4.

Fig. 5.
